CLAIM

The ornamental design for a device for monitoring process equipment, as shown and described.

DESCRIPTION

FIG. 1 is a front, right, top perspective view of a device for monitoring process equipment showing my new design;

FIG. 2 is a front view thereof;

FIG. 3 is rear view thereof;

FIG. 4 is left side view thereof;

FIG. 5 is a right side view thereof; and,

FIG. 6 is a top view thereof.

The broken lines in the drawings illustrate portions of the device for monitoring process equipment that form no part of the claimed design.
